ABSTRACT

A boxer brief includes a body portion, a waist band, a left leg portion, a right leg portion, a front pouch disposed about a front region of the body portion, a means for providing support to the front pouch via the front pouch being connected to a bottom horizontal seam entirely above the first leg opening and the second leg opening, and a means for separating at least a portion of an external male genitalia of the wearer from at least a portion of an inner thigh of the wearer.

LOWER TORSO GARMENT WITH SUPPORT ELEMENT

CROSS-REFERENCE TO RELATED APPLICATIONS

This application is a Continuation of and claims the benefit of U.S. patent application Ser. No. 17/238,665, filed Apr. 23, 2021, which is a Continuation of U.S. National Phase application Ser. No. 16/090,539, filed Oct. 1, 2018, which claims the benefit of priority to International Application Serial No. PCT/US2017/027496, filed Apr. 13, 2017, which claims priority to U.S. Provisional Application Ser. No. 62/322,779, filed Apr. 14, 2016, the contents of which are hereby incorporated by reference.

BRIEF SUMMARY OF THE INVENTION

This disclosure relates to lower torso garments having support elements, such as men's underwear.

SUMMARY

A boxer brief is provided. In one embodiment, the boxer brief comprises a body portion, a waistband attached to a top end of the body portion and configured to encircle a torso of a wearer, a left leg portion comprising a first leg opening at a lower longitudinal end of the left leg portion, a right leg portion comprising a second leg opening at a lower longitudinal end of the right leg portion, a front pouch disposed about a front region of the body portion, a means for providing support to the front pouch via the front pouch being connected to a bottom horizontal seam entirely above the first leg opening and the second leg opening, and a means for separating at least a portion of an external male genitalia of the wearer from at least a portion of an inner thigh of the wearer.

In another embodiment, a lower torso garment comprises a waistband at an upper end of the lower torso garment, a body portion, and a front pouch disposed about a front region of the body portion and further defining a pass-through fly opening. A support element includes a left fabric panel comprising a left lateral seam and an exterior left lateral seam on the opposing side of the left fabric panel, the exterior left lateral seam extending along a left side periphery of the front pouch and connected to a bottom horizontal seam, and a right fabric panel comprising a right lateral seam and an exterior right lateral seam on the opposing side of the left fabric panel, the exterior left lateral seam extending along the left side periphery of the front pouch and connected to the bottom horizontal seam. The body portion, the front pouch, and the support element separate at least a portion of an external male genitalia of a wearer from at least a portion of an inner thigh of the wearer.

In another embodiment, a boxer brief comprises a waistband at an upper end of the boxer brief, a mesh body portion, a left leg portion comprising a first leg opening at a lower longitudinal end of the left leg portion, a right leg portion comprising a second leg opening at a lower longitudinal end of the right leg portion, a front pouch disposed about a front region of the mesh body portion and including a vertical seam extending through a central portion thereof, a bottom horizontal seam at a bottom of the front pouch, and the bottom horizontal seam being entirely above the first leg opening and the second leg opening. A support sling is connected to the front pouch, the support sling including a left fabric panel comprising a left lateral seam attaching the

left fabric panel to the mesh body portion along an entirety thereof and an exterior portion of the left fabric panel in communication with the bottom horizontal seam. A right fabric panel comprises a right lateral seam attaching the right fabric panel to the mesh body portion along an entirety thereof, and an exterior portion of the right fabric panel in communication with the bottom horizontal seam. A first portion of the left fabric panel overlaps a first portion of the right fabric panel at an overlap area, the overlap area positioned adjacent to the bottom horizontal seam at the bottom of the front pouch.

In one embodiment, the means for providing support to the front pouch further comprises a gusset positioned at a bottom of the boxer brief between the left leg portion and the right leg portion.

In one embodiment, the means for separating at least the portion of the external male genitalia of the wearer from the at least a portion of the inner thigh of the wearer includes a support sling comprising a pocket positioned adjacent to a bottom of an interior surface of the front pouch.

In one embodiment, the means for separating at least a portion of the external male genitalia of the wearer from at least a portion of the inner thigh of the wearer comprises a first support element connected to the front pouch and a second support element connected to the front pouch.

In one embodiment, the gusset is connected to the front pouch with the bottom horizontal seam at a bottom of the front pouch.

In one embodiment, the support sling comprises a left fabric panel proximate a left side periphery of the front pouch and a right fabric panel proximate a right side periphery of the front pouch.

In one embodiment, the left fabric panel comprises a left lateral seam and an exterior left lateral seam on the opposing side of the left fabric panel, the exterior left lateral seam extending along the left side periphery of the front pouch and connected to the bottom horizontal seam, and the right fabric panel comprises a right lateral seam and an exterior right lateral seam on the opposing side of the right fabric panel, the exterior right lateral seam extending along the right side periphery of the front pouch and connected to the bottom horizontal seam.

In one embodiment, the left fabric panel and the right fabric panel are provided in a first color and the front pouch is provided in a second color different from the first color.

In one embodiment, the left fabric panel and the right fabric panel are provided in the first color and the waistband is also provided in the first color.

In one embodiment, the front pouch further includes a vertical seam disposed between the left fabric panel and the right fabric panel.

In one embodiment, a vertical seam connects to the waistband and the bottom horizontal seam.

In one embodiment, a vertical seam of the front pouch extends between the waistband and the bottom horizontal seam and defines a pouch seam length.

In one embodiment, the front pouch further includes a vertical seam extending between the waistband and the bottom horizontal seam.

In one embodiment, the bottom horizontal seam is connected to a left leg seam and a right leg seam that are adjacent the first leg opening and the second leg opening, respectively.

In one embodiment, the bottom horizontal seam is connected to a left leg seam and a right leg seam that are adjacent the first leg opening and the second leg opening, respectively.

In one embodiment, the front pouch further includes a pass-through fly opening having an overlap for through-access of all or a portion of the external male genitalia to be exposed exterior to the boxer brief through the pass-through fly opening when the boxer brief is worn by the wearer.

In one embodiment, a length of the overlap area is less than 1/4 of a total seam length of the front pouch.

In one embodiment, the first support element is configured to separate a first portion and a second portion of the external male genitalia from the inner thigh of the wearer, and the second support element is configured to separate the first portion of the external male genitalia from the second portion of the external male genitalia.

BRIEF DESCRIPTION OF THE DRAWINGS

FIG. 1 is a front view of an example lower torso garment.

FIGS. 2A-2C are cross-sectional interior front views of example lower torso garments with support structures.

FIG. 3 is a front view of an example lower torso garment.

FIGS. 4A-4B are a front view and a cross-sectional interior front view of an example lower torso garment.

Like reference numbers and designations in the various drawings indicate like elements.

DETAILED DESCRIPTION

This disclosure describes support elements for lower torso garments, for example men's underwear (e.g., boxers, boxer-briefs, briefs, and/or others). Support elements can take a variety of forms, for example, depending on the intended location of support, lower torso garment type, function, flexibility, and/or other factors. Support elements described herein can be used to support at least a portion of the external male genitalia of a wearer of the lower torso garment, where the wearer's external male genitalia is disposed proximate a front pouch region of the lower torso garment. The front pouch region can include a variety of support elements that can provide support for all or a portion of the external male genitalia. For example, the lower torso garment can include a support sling surrounding (partially, substantially, or completely) the front pouch, such as about a periphery of the front pouch. The support sling can include support panels, such as web-like mesh fabric layers, shaped to define, in part, a partially enclosed sling region for at least a portion of the external male genitalia of a wearer to be disposed, where the sling region can include an area between an interior surface of the front pouch and the support panels of the support sling. In some instances, the support elements can include a stitch line or a stitch seam across or along a lower portion of the front pouch of the lower torso garment to provide stretchability, support, or both stretchability and support to the front pouch supporting the male anatomy of a wearer.

FIG. 1 is a front view of an example lower torso garment 100, for example, a men's boxer brief. The lower torso garment includes a waistband 102 at an upper end of the lower torso garment 100, and a body region 104 including a front pouch 106, a rear buttocks area (not shown), and a left leg region 108a and a right leg region 108b, each with respective leg openings 110a and 110b at lower ends of the respective left leg region 108a and right leg region 108b. The waistband 102 has a torso-encircling shape, and connects to the body region 104, for example, via seamless knitting, stitching, fusing, bonding, adhering, or other connections. With a wearer wearing the example lower torso garment 100, the waistband encircles a torso of the wearer,

the front pouch 106 resides adjacent to and supporting at least a portion of the external male genitalia of the wearer, the buttocks region resides adjacent to the buttocks of a wearer, and the left and right leg regions 108a and 108b receive the legs of the wearer. The front pouch 106 is shown in FIG. 1 as stitched to adjacent fabric of the body region 104 at lateral seams, for example, a left pouch seam 112a and a right pouch seam 112b; however, the front pouch 106 can connect to adjacent fabric of the body region 104 in a variety of other ways. For example, the front pouch 106 can connect to the adjacent fabric of the body region 104 by knitting (e.g., seamless knitting), stitching, fusing, bonding, adhering, or other connections.

In some implementations, the front pouch 106 of the lower torso garment 100 includes a support element or multiple support elements to provide support, reinforcement, and/or comfort to the front pouch 106 and/or to a wearer of the lower torso garment 100. In certain instances, the support element includes a flexible fabric, such as a flexible mesh fabric. However, the material of the support element can vary, and can be more flexible, less flexible, or the same flexibility as the fabric of the front pouch 106 and/or body region 104. In some examples, the support element of the front pouch 106 includes a support sling disposed at an interior of the garment. The support sling can take a variety of forms, as described in more detail below. In some instances, the body region 104 includes a gusset portion at a bottom of the lower torso garment 100 between the leg regions 108a and 108b. The lower torso garment 100 can be manufactured in a variety of ways, such as circularly knitting all or most of the lower torso garment 100, cutting fabric to form portions of the lower torso garment 100, and/or stitching together the cut portions of the lower torso garment 100 at stitches or seams joining the garment portions, such as at areas indicated in the drawings. The front pouch 106 can be knit to the body region 104, shown in FIG. 1 as knit at the left and right lateral seams 112a and 112b about the front portion and a bottom horizontal seam 114 proximate the gusset. In some examples, such as shown in FIGS. 4A and 4B and described in more detail later, the front pouch can include a pass-through fly opening including an overlap, for example, for through-access of all or a portion of the external male genitalia to be exposed exterior to the garment through the pass-through when the garment is worn by the wearer.

FIG. 2A is a cross-sectional interior front view of an example lower torso garment 200 showing the interior of the front of the lower torso garment 200, for example, the portions of the interior front of the lower torso garment 200 that engage the skin of a wearer of the lower torso garment 200. Example lower torso garment 200 is like the lower torso garment 100 of FIG. 1, except the example lower torso garment 200 includes a support element in the form of a support sling 202 disposed within the body region 104 (i.e., at an interior of the garment) proximate the front pouch 106 and along the left and right lateral seams 112a and 112b that substantially define the lateral periphery of the front pouch 106. The support sling 202 includes a left fabric panel 204 and a right fabric panel 206 extending from a bottom edge of the front pouch 106 to a top edge of the front pouch adjacent the waistband 102.

Referring to the example lower torso garment of FIG. 2A, the left fabric panel 204 and the right fabric panel 206 of the support sling 202 are disposed in a criss-cross pattern and reside on either side of the front pouch 106 proximate one of the substantially vertical seams 112a and 112b on the lateral sides of the front pouch 106. The left fabric panel 204

and the right fabric panel 206 can each include a web of fabric that attaches to a periphery of the front pouch 106 and extends between a top and a bottom of the front pouch 106. The left fabric panel 204 and the right fabric panel 206 overlay at least a portion of the fabric of the front pouch 106, for example, to create a pocket for the external male genitalia of the wearer, where all or at least a portion of the external male genitalia of the wearer resides and is supported within the pocket between the fabric of the front pouch 106 and the left and right fabric panels 204 and 206. In some examples, the left fabric panel 204 and the right fabric panel 206 reside between at least a portion of the external male genitalia of the wearer and the inner thigh of the wearer to act as a fabric barrier between skin contact of the inner thigh and the external male genitalia of the wearer. As shown in FIG. 2A, the left fabric panel 204 and the right fabric panel 206 are substantially symmetrical across a vertical centerline of the garment, for example, across a centerline of the front pouch 106. A long-edge of each fabric panel attaches along its edge length to the left or right lateral seam (112a or 112b, respectively) of the front pouch 106, and a first short edge at one end of each fabric panel attaches proximate the waistband 102 and a second short edge at its other end (e.g., opposite the first short edge) is attached at a bottom of the front pouch 106 (e.g., at the gusset). Each of the fabric panels criss-cross, or twist, between its connection proximate the waistband 102 and its connection at the bottom of the front pouch 106. For example, the left fabric panel 204 criss-crosses along its longitudinal length as it extends from the top of the front pouch 106 to the bottom of the front pouch 106. Similarly, the right fabric panel 206 criss-crosses along its longitudinal length as it extends from the top of the front pouch 106 to the bottom of the front pouch 106. At the one end proximate the waistband 102, the first short edge of the fabric panel (e.g., left fabric panel 204 or right fabric panel 206) extends substantially outwardly (e.g., toward a wearer's side) along the waistband 102, while the second short edge extends substantially inwardly, opposite the direction of first short edge. As shown in FIG. 2A, the left fabric panel 204 and the right fabric panel 206 overlap at an overlap area 208 near a bottom of the front pouch 106, where the overlapped edge of the left fabric panel 204 is indicated in a dashed line. The widths of the left fabric panel 204 and the right fabric panel 206 can partially or completely overlap at its lower attachment to the bottom of the front pouch 106. As the left fabric panel 204 and right fabric panel 206 extend upwards toward the waistband, the overlap area 208 decreases until the fabric panels no longer overlap, creating a substantially triangular area of the overlap area 208.

The left fabric panel 204 and the right fabric panel 206 can include a plurality of materials and fabrics. For example, the fabric panels can include a flexible fabric, such as a flexible mesh fabric, a fabric web, taping, or other material. The material of the support element can vary, and can be more flexible, less flexible, or the same flexibility as the fabric of the front pouch and/or body region. In some instances, the fabric of the body region 104 can include cotton, spandex, a combination of these, and/or other material, the front pouch fabric can include cotton, spandex, a combination of these, and/or other material, the thread (e.g., the seams) can include polyester, cotton, and/or other material, the waistband 102 can include polyester, spandex, and/or other material, and the support sling (e.g., support sling 202) can include polyester, spandex, and/or other material. For example, the fabric panels of the support sling can include a knitted synthetic mesh fabric, such as knitted

polyester fiber, a lightweight jersey (e.g., cotton) fabric, can include ventilation openings, and can include spandex or other elastomeric material. The left and right fabric panels can have zero stretch or some degree of stretch (e.g., up to 10%, 20%, 30%, 50%, or more stretch), and the stretch can include a material stretch or a mechanical stretch (e.g., cotton ribs).

In some instances, the support sling (e.g., criss-cross support sling 202) is integrated into the make or construction 10 of the lower torso garment (e.g., boxer brief, or lower torso garment 200) to provide enhanced support as a result of adding the criss-crossed support sling 202 proximate the area of the front pouch 106. By adding the inner sling to the inside of lower torso garment at the front pouch and criss 15 crossing the sling layers (e.g., fabric panels, or webs) at a bottom portion of pouch, the wearer noticeably feels more support, for example, than when wearing a lower torso garment without a sling in the pouch. The sling can be accomplished by using two panels of light weight stretch 20 fabric criss crossed at bottom portion of pouch inside the garment. In some implementations, the criss cross support sling can be added to the pattern for garment make-up and stitched into the seams during construction.

The shape and placement of the support sling can vary. 25 For example, FIG. 2B is a cross-sectional interior front view of an example lower torso garment 210 with a support sling 212, where FIG. 2B shows the interior of the front of the lower torso garment 210. The example lower torso garment 210 and support sling 212 are like the example lower torso garment 200 and support sling 202 of FIG. 2A, except the support sling 212 of lower torso garment 210 includes a substantially planar left fabric panel 214 and right fabric panel 216, where the left fabric panel 214 and right fabric panel 216 do not include a criss-cross, or twist, as the panels 30 extend vertically along the front pouch 106. Instead, a periphery of the support sling 212 remains within the periphery of the front pouch 106. The left fabric panel 214 and the right fabric panel 216 include the overlap area 208 near a bottom of the front pouch 106, where the overlapped edge of the right fabric panel 216 is shown in a dashed line. 35 A laterally outside edge of the left fabric panel 214 connects to and extends along the left lateral seam 112a, and a laterally outside edge of the right fabric panel 216 connects to and extends along the right lateral seam 112b. Top edges 40 of the left fabric panel 214 and right fabric panel 216 extend laterally inwardly towards each other, leaving a gap between the top edges and the inner edges of the fabric panels that define an opening, for example, for a portion of the external 45 male genitalia to pass through when a wearer wears the lower torso garment 210.

FIG. 2C is a cross-sectional interior front view of an example lower torso garment 220 with a support sling 222, where FIG. 2C shows the interior of the front of the lower torso garment 220. The example lower torso garment 220 and support sling 222 are like the example lower torso garments 200 and 210 and support slings 202 and 212 of FIGS. 2A and 2B, respectively, except the support sling 222 of lower torso garment 220 includes a substantially planar left fabric panel 224 and right fabric panel 226 that overlap 50 each other at a first overlap area 228 at a bottom of the front pouch 106 and also overlap each other at a second overlap area 230 at a top of the front pouch 106. For example, a first portion of the left fabric panel 224 overlaps a first portion of the right fabric panel 226 to define the first overlap area 228, and a second portion of the left fabric panel 224 overlaps a second portion of the right fabric panel 226 to define the second overlap area 230. FIG. 2C shows the first overlap

area 228 and second overlap area 230 as substantially the same size; however, the overlap area can be different. For example, the first overlap area 228 can be larger or smaller than indicated in FIG. 2C, and can be larger or smaller than the second overlap area 230. Similarly, the second overlap area 230 can be larger or smaller than indicated in FIG. 2C, and can be larger or smaller than the first overlap area 228.

In some instances, constructing the example lower torso garment (e.g., lower torso garment 200, 210, 220) includes determining the correct placement for the support sling (e.g., support sling 202, 212, 222) on the lower torso garment by fitting the lower torso garment on a fit model and analyzing original garment specs of the lower torso garment (e.g., boxer brief) in which the support sling is to be added. Once placement and pattern are determined, two panels of fabric can be added, one to each side of the pouch inside of garment (at seaming). In some examples, the support sling can be sewn into the garment using the correct stretch direction for the fabric used as the sling. Edges of the sling fabric panels can be edged using a purl stitch, an over edge stitch, a finished edge, a laser-cut edge, a finished seam, a folded seam, or other edge type.

Referring to the example lower torso garment 220 shown in FIG. 2C, the support sling 222 is a key-hole shaped support sling. The keyhole support sling 222 is disposed on an interior of the boxer-brief lower torso garment 220 and lines the periphery of the front pouch 106. The left fabric panel 224 and right fabric panel 226 of the support sling 222 at least partially overlap at the second overlap area 230 at an upper end of the front pouch 106 and at the first overlap area 228 at a lower end of the front pouch 106. A long-edge of each panel of the left fabric panel 224 and the right fabric panel 226 attaches along its edge length to the left or right lateral seam of the front pouch 106, and a first short edge at one end is attached proximate the waistband and the second short edge at its other end is attached at the bottom of the front pouch 106 (e.g., at the gusset). Both the short edges extend substantially inwardly, and can overlap at the upper seam and lower seam of the front pouch 106. The fabric panels create a keyhole-shaped opening between the two fabric panels. The fabric panels can include a plurality of materials and fabrics. In the example lower torso garment 220 of FIG. 2C, the fabric panels include a mesh fabric.

In some instances, the keyhole support sling can be constructed by adding to each side of the pouch inside of the lower torso garment (e.g., at the seaming) the two pieces of fabric that cross over one another at the top and bottom of pouch to create the key hole sling and support for the wearer. The keyhole support sling can be sewn into the garment using the correct stretch direction for the sling fabric. Edges of sling fabric panels can be edged using a purl over edge stitch for comfort.

The left fabric panel (204, 214, 224) and the right fabric panel (206, 216, 226) of the support sling (202, 212, 222) of the lower torso garments (200, 210, 220) of FIGS. 2A-2C can be disposed in a variety of locations and positions, and can include various materials and constructions. For example, the left and right fabric panels can include a single ply fabric panel or a multi-ply fabric panel (e.g., dual ply fabric panel), and the inner edges of the fabric panels can include a purl stitch, an over-edge stitch, a finished edge, a laser-cut edge, a finished seam, a folded seam, or other edge type.

The front pouch 106 can act as a basket sling that acts as a support basket for the external male genitalia of a wearer,

and can provide for multi-directional support of the external male genitalia, for example, during movement and/or activity of the wearer.

FIG. 3 is a front view of an example lower torso garment 300, similar to the lower torso garments 200, 210, 220 of FIGS. 2A-2C, except (at least) the front pouch includes a support element in the form of a support stitch line 302 extending horizontally (substantially or exactly) between the lateral side seams 112a and 112b at the periphery of the front pouch 106, and the lower torso garment 300 includes a pass-through fly opening 304 including an overlap, for example, for through-access of the external male genitalia to be exposed exterior to the garment through the pass-through when the garment is worn by the wearer. The example lower torso garment 300 of FIG. 3 does not include a support sling described earlier with respect to FIGS. 2A-2C; however, the example lower torso garment 300 can include one or more of the other support elements, support structures, and/or support slings described herein. In some instances, the lower torso garment 300 excludes the fly opening 304. The support stitch line 302 is illustrated as extending between the left and right lateral seam 112a and 112b of the front pouch 106 proximate a front-bottom area of the front pouch. The horizontal seam extends between the left and right front pouch seam to provide support for the crotch region of a wearer of the garment. The horizontal seam can include a cover stitch, over edge stitch, flatlock seam, or other type of stitch or seam. The SPI (stitches per inch) can vary. For example, the SPI can be about 13 (e.g., between 11 and 15), or different (e.g., between 5 and 20). The front pouch 106 can include two layers of fabric (e.g., two-ply fabric), and the horizontal seam can be sewn through both layers of the front pouch fabric.

The type and placement of the support stitch line 302 can vary. For example, FIG. 3 shows the support stitch line 302 as placed just below the fly opening 304 (e.g., within one or two inches of the fly opening edge), about two-thirds (2/3) down the longitudinal length of the front pouch 106 from the top of the front pouch 106, or one-third (1/3) up the longitudinal length of the front pouch 106 from the bottom of the front pouch 106. However, the location of the support stitch line 302 can vary, for example, the support stitch line 302 can be located vertically higher or lower than the position indicated in FIG. 3.

The support stitch line 302 can take a variety of forms. Although the support stitch line 302 is described herein in some instances as including a seam, the support stitch line 302 may not be a seam or a stitch. Instead, the support stitch line 302 can include a support element, such as a tape or other attachment that can fuse, bond, adhere, or otherwise attach to the front pouch 106 of the lower torso garment 300, between fabric layers of the front pouch 106, or otherwise connect to the front pouch. For example, the support stitch line 302 can include a stitch-sew line extending laterally across the front pouch 106, taping that is fused, adhered, or otherwise attached to the front pouch, other material that is fused or bonded to the fabric of the front pouch 106, sew thread that is knit, woven, stitched, or otherwise connected to the front pouch, and/or other materials. In some examples, the support stitch line 302 includes a width of up to an inch (e.g., 1/4 inches, 1/2 inches, 3/4 inches, or another width dimension). In some instances, the support stitch line 302 can provide some degree of stretch. In some examples, the support stitch line 302 has less stretch than the fabric of the front pouch 106, for example, to provide strength and/or support to the front pouch in addition to or in lieu of a gusset.

FIGS. 4A and 4B are a front view and a cross-sectional interior front view, respectively, of an example lower torso garment 400, similar to lower torso garment 300 of FIG. 3, where the example lower torso garment includes a support stitch line 402 extending horizontally (substantially or exactly) between the lateral side seams 112a and 112b at the periphery of the front pouch 106. FIG. 4B shows the interior of the front of the example lower torso garment 400. In some instances, such as shown in the example lower torso garment 400 of FIGS. 4A and 4B, the support stitch line 402 is a horizontal support seam that creates gathers 404 in the fabric about (e.g., surrounding) a support seam. In some instances, this support stitch line 402 includes one or more elastic elements 406 (e.g., elastomeric elements, or other elements effecting an elastic/elastomeric/stretch characteristic of the stitch) integrated into the support stitch line 402, for example, at an interior side of the front pouch 106. The elastic element(s) 406 biases the horizontal support stitch line 402 to compress edges of adjacent fabric edges to create the fabric gathers 404 (e.g., extra body fabric, fabric folds, fabric wrinkles, and/or other forms of gathers) in the fabric of the front pouch 106 surrounding the horizontal support stitch line 402. The fabric gathers 404 allow a greater degree of stretch to the fabric of the front pouch 106 (e.g., than fabric without gathers), and allows space for the external male genitalia of a wearer of the lower torso garment 400. The support stitch line 402 can extend between a left and right seam of the front pouch 106 proximate a front-bottom area of the front pouch 106, and includes the elastic element 406.

The type and placement of the support stitch line 402 can vary. For example, FIGS. 4A and 4B show the support stitch line 402 as placed below the fly opening 304 (e.g., within one or two inches of the fly opening edge). However, the location of the support stitch line 402 can vary, for example, the support stitch line 402 can be located vertically higher or lower than the position indicated in FIGS. 4A and 4B.

The support stitch line 402 can take a variety of forms. Although the support stitch line 402 is described herein in some instances as including a seam, the support stitch line 402 may not be a seam or a stitch. Instead, the support stitch line 402 can include a support element, such as a tape or other attachment that can fuse, bond, adhere, or otherwise attach to the front pouch 106 of the lower torso garment 400, between fabric layers of the front pouch 106, or otherwise connect to the front pouch. For example, the support stitch line 402 can include a stitch-sew line extending laterally across the front pouch 106, taping that is fused, adhered, or otherwise attached to the front pouch, other material that is fused or bonded to the fabric of the front pouch 106, sew thread that is knit, woven, stitched, or otherwise connected to the front pouch, and/or other materials. In some examples, the support stitch line 402 includes a width of up to an inch (e.g., $\frac{1}{4}$ inches, $\frac{1}{2}$ inches, $\frac{3}{4}$ inches, or another width dimension). In some instances, the support stitch line 402 can provide some degree of stretch. In some examples, the support stitch line 402 has less stretch than the fabric of the front pouch 106, for example, to provide strength and/or support to the front pouch in addition to or in lieu of a gusset.

In some instances, the horizontal support stitch line 402 and adjacent portions of the left lateral side seam 112a and right lateral side seam 112b of the front pouch 106 (e.g., portions of the left and right seams extending upward from the horizontal seam) can include elastic elements 408 stitched, tacked, bonded, fused, or otherwise integrated into the lateral side seams 112a and 112b. The elastic elements 408 can extend to a portion of the length of the lateral side

seams 112a and 112b, for example, $\frac{1}{4}$ of the length, $\frac{1}{3}$ of the length, or another portion of the length of the lateral side seams 112a and 112b beginning at the intersection of the support stitch line 402 and the respective lateral side seams 112a and 112b of the front pouch 106. In some examples, the generally vertical elastic elements 408 extend along the sew line of the lateral side seams 112a and 112b, while the elastic element 406 of the horizontal support stitch line 402 extends across the fabric of the front pouch 106. In some implementations, the elastic element 406 and/or the elastic elements 408 are stitched when in a stretched state and where the adjacent fabric is in a relaxed (e.g., un-stretched state), and where returning the elastic element(s) to its un-stretched state creates the fabric gathers 404 about the horizontal support stitch line 402 and/or the adjacent portions of the left lateral side seam 112a and right lateral side seam 112b of the front pouch 106. The elastic elements and the fabric gathers 404 provide for a volume (e.g., increased volume) of the sling region while maintaining, increasing, or otherwise affecting the support of the front portion at the horizontal seam and/or at other seam areas. The elastic element 406 and/or the elastic elements 408 can take a variety of forms. For example, an elastic element can include a strip or band of elastomeric material, an elastomeric thread, a stretchy sew tape, or other elements with a degree of stretch greater than the degree of stretch of the fabric of the front pouch 106. Although the support stitch line 402 is described herein in some instances may include a seam, the support stitch line 402 may not be a seam or a stitch. Instead, the support stitch line 402 can include a support element, such as a tape or other attachment that can fuse, bond, adhere, or otherwise attach to the front pouch 106 of the lower torso garment 400.

In some instances, the gathered horizontal stitch line or seam is constructed by determining the correct placement of the gathered stitch line or seam on the lower torso garment, which is done by fitting on a fit model and analyzing original garment specs of the boxer brief in which the stitch line or seam is to be added. Once placement is determined, elastic can be added to the inside of garment at bottom of pouch while stretching the elastic during sewing to create gathers in the fabric. The SPI (stitches per inch) can include an SPI of 13, but can vary, for example, between 5 and 20. The gathering stitches work best (e.g., supports best) when sewn through both layers of the pouch fabric.

A gathered support pouch creates support for the wearer of the lower torso garment. A conventional way to add support on this type of garment is by adding a gusset. A gusset can include a piece of fabric, generally in a rectangle or diamond shape, inserted in a garment to allow for more space and greater ease of movement. In men's underwear, for example, the gusset appears along the inseams and crotch area of garment. Although a conventional gusset does provide support, it may not provide any additional shaping to a front pouch, whereas a gathered pouch does provide an increase in support and comfort for the wearer.

A number of implementations have been described. Nevertheless, it will be understood that various modifications may be made without departing from the spirit and scope of the disclosure.

The invention claimed is:

1. A boxer brief, comprising:
a body portion;
a waistband attached to a top end of the body portion and configured to encircle a torso of a wearer;
a left leg portion comprising a first leg opening at a lower longitudinal end of the left leg portion;

11

a right leg portion comprising a second leg opening at a lower longitudinal end of the right leg portion; a front pouch disposed about a front region of the body portion; and

5 a support element including:

a first fabric panel including a first wearer-facing surface imparted with a first surface area,

a second fabric panel including a second wearer-facing surface imparted with a second surface area, and

10 an overlap area defined by a first portion of the first fabric panel that overlays a second portion of the second fabric panel,

wherein the overlap area is imparted with a third surface area;

15 wherein the first fabric panel comprises a left lateral seam and the second fabric panel comprises a right lateral seam;

wherein a first elastomeric element couples to the first fabric panel and is positioned adjacent to the left lateral seam; and a second elastomeric element couples to the second fabric panel and is positioned adjacent to the right lateral seam.

2. The boxer brief of claim 1 further comprising a gusset positioned at a bottom of the boxer brief between the left leg portion and the right leg portion.

3. The boxer brief of claim 2, wherein the gusset is connected to the front pouch with a bottom horizontal seam positioned at a bottom of the front pouch.

4. The boxer brief of claim 1, wherein the first and second fabric panels comprise a support sling and the first portion of the first fabric panel and the second portion of the second fabric panel comprise a pocket positioned adjacent to a bottom of an interior surface of the front pouch.

5. The boxer brief of claim 4, wherein the first fabric panel is a left fabric panel proximate a left side periphery of the front pouch, and wherein the second fabric panel is a right fabric panel proximate a right side periphery of the front pouch.

6. The boxer brief of claim 5, wherein the left fabric panel comprises the left lateral seam and an exterior left lateral seam on the opposing side of the left fabric panel, the exterior left lateral seam extending along the left side periphery of the front pouch and connected to a bottom horizontal seam of the boxer brief, and the right fabric panel comprises the right lateral seam and an exterior right lateral seam on the opposing side of the right fabric panel, the exterior right lateral seam extending along the right side periphery of the front pouch and connected to the bottom horizontal seam.

7. The boxer brief of claim 6, wherein the bottom horizontal seam is connected to a left leg seam and a right leg seam that are adjacent the first leg opening and the second leg opening, respectively.

8. The boxer brief of claim 5, wherein the front pouch further includes a vertical seam disposed between the left fabric panel and the right fabric panel.

9. The boxer brief of claim 8, wherein the vertical seam connects to the waistband and a bottom horizontal seam of the boxer brief.

10. The boxer brief of claim 1, wherein the front pouch further includes a pass-through fly opening having an overlap for through-access of all or a portion of an external male genitalia to be exposed exterior to the boxer brief through the pass-through fly opening when the boxer brief is worn by the wearer.

11. The boxer brief of claim 1, wherein the overlap area is positioned adjacent to a bottom of the front pouch.

12

12. A lower torso garment, comprising:

a waistband at an upper end of the lower torso garment; a body portion;

a front pouch disposed about a front region of the body portion and further defining a pass-through fly opening; a support element comprising:

a left fabric panel comprising a left lateral seam and an exterior left lateral seam on the opposing side of the left fabric panel, the exterior left lateral seam extending along a left side periphery of the front pouch and connected to a bottom horizontal seam;

a right fabric panel comprising a right lateral seam and an exterior right lateral seam on the opposing side of the right fabric panel, the exterior right lateral seam extending along a right side periphery of the front pouch and connected to the bottom horizontal seam; a first elastomeric element coupled to the left fabric panel and positioned adjacent to the left lateral seam; and

a second elastomeric element coupled to the right fabric panel and positioned adjacent to the right lateral seam,

wherein the body portion, the front pouch, and the support element are designed to separate at least a portion of an external male genitalia of a wearer from at least a portion of an inner thigh of the wearer, and

wherein a first portion of the left fabric panel overlaps a second portion of the right fabric panel at an overlap area.

13. The lower torso garment of claim 12, wherein the first elastomeric element extends along a length of the left lateral seam, and wherein the second elastomeric element extends along a length of the right lateral seam.

14. The lower torso garment of claim 12, wherein the left fabric panel and the right fabric panel are provided in a first color and the front pouch is provided in a second color different from the first color.

15. The lower torso garment of claim 12, wherein the left fabric panel and the right fabric panel are provided in a first color and the waistband is also provided in the first color.

16. A boxer brief, comprising:

a waistband at an upper end of the boxer brief;

a mesh body portion;

45 a left leg portion comprising a first leg opening at a lower longitudinal end of the left leg portion;

a right leg portion comprising a second leg opening at a lower longitudinal end of the right leg portion;

a front pouch disposed about a front region of the mesh body portion and including a vertical seam extending through a central portion thereof;

a bottom horizontal seam at a bottom of the front pouch, and the bottom horizontal seam being entirely above the first leg opening and the second leg opening;

55 a support sling connected to the front pouch, the support sling comprising:

a left fabric panel comprising a left lateral seam attaching the left fabric panel to the mesh body portion along an entirety thereof, and an exterior portion of the left fabric panel in communication with the bottom horizontal seam, wherein the left fabric panel is imparted with a first surface area;

a right fabric panel comprising a right lateral seam attaching the right fabric panel to the mesh body portion along an entirety thereof, and an exterior portion of the right fabric panel in communication with the bottom horizontal seam, wherein the right fabric panel is imparted with a second surface area;

13

a first elastomeric element positioned and extending substantially vertically along an edge of the left fabric panel; and
a second elastomeric element positioned and extending substantially vertically along an edge of the right fabric panel,
wherein a first portion of the left fabric panel overlaps a first portion of the right fabric panel at an overlap area, the overlap area positioned adjacent to the bottom horizontal seam at the bottom of the front pouch. 10

17. The boxer brief of claim **16**, wherein the vertical seam of the front pouch extends between the waistband and the bottom horizontal seam and defines a pouch seam length. 15

18. The boxer brief of claim **17**, wherein a length of the overlap area is less than $\frac{1}{4}$ of the pouch seam length.
19. The boxer brief of claim **16**, wherein the bottom horizontal seam is connected to a left leg seam and a right leg seam that are adjacent the first leg opening and the second leg opening, respectively. 20
